UNITED STATES PATENT OFFICE

EDWIN SMILEY, OF PENFIELD, PENNSYLVANIA

FURNACE STRUCTURE

Application filed October 27, 1927. Serial No. 229,063.

My invention relates to furnace structures of the type wherein provision is made for the circulation of air to maintain the lining of the furnace in a relatively cool condition. 5 More specifically considered, my invention relates to special forms of blocks for lining furnaces, which blocks are adapted to be used in conjunction with bricks of ordinary shape for building walls, floors, etc., of furnaces. 10 Heretofore, in the construction of furnaces having air cooled linings, considerable difficulty has been experienced in so constructing the furnace that the component parts of the same are properly and sufficiently bonded to prevent separation thereof when the furnace walls are subjected to expansion and contraction by reason of the high temperature ranges in the interior of the furnace. This difficulty is experienced in 15 furnace walls where special forms of blocks, having air conduits provided thereby, are used in connection with bricks of ordinary shape, as well as in those furnace walls in which the lining is made of ordinary fire 20 brick.

The principal object, therefore, of my present invention is to provide a furnace structure made up of special forms of blocks having air conduits molded therein, used in 25 connection with bricks of ordinary shape, in which the various parts are securely bonded, to the end that the structure will not disintegrate in use as rapidly as heretofore. A further object of my invention is to provide 30 improved forms of blocks for lining furnaces of the air cooled type, which blocks may be readily and easily molded. A further object of my invention is to provide an air cooled furnace wall construction in which baffles 35 may be readily inserted to insure the circulation of the cooling air through all parts of the wall.

A further object of my invention is to provide such special forms of blocks which 40 may be used not only for the walls, but also for the floors of furnaces, whereby the floors as well as the vertical walls may be air cooled, to decrease adherence of slag to the floors. 45 A further object of my invention is to provide such special forms of blocks which are

not only adapted for lining the furnace walls, but are also adapted for use in connection with bricks of ordinary shape in providing floor structures for oil fired or other furnaces, in which it is desirable to 55 admit a certain amount of air from various parts of the floor. A further object of my invention is to provide a furnace structure of the air cooled type in which a minimum number of special forms of blocks are required for fabricating the walls. A further 60 object of my invention is to provide a furnace structure of the air cooled type in which any of the courses of the blocks of the lining may be removed and replaced without 65 interfering with the remaining structure of the wall, and in which, for the purposes of repair, fire brick may be substituted for one or more of the lining blocks.

The nature and characteristic features of 70 my invention will be more readily understood from the following description, taken in connection with the accompanying drawings forming part hereof, in which:

Figure 1 is a front elevation of a portion 75 of a furnace wall embodying the main features of my present invention;

Fig. 2 is a vertical section thereof, taken approximately on the line 2—2 of Fig. 1;

Fig. 3 is a horizontal section thereof, taken 80 approximately on the line 3—3 of Fig. 2;

Fig. 4 is a horizontal section thereof, taken approximately on the line 4—4 of Fig. 2;

Fig. 5 is a perspective view of one of the 85 special forms of blocks used in the structure;

Fig. 6 is a similar view of another form of block used in connection therewith;

Fig. 7 is a front elevation, partly broken away, illustrating the manner of placing 90 bricks of ordinary shape in certain of the air conduits for the purpose of forming baffles to deflect the cooling air in the wall conduits, to insure complete circulation of the air through all portions of the wall;

Fig. 8 is a vertical section thereof, taken 95 approximately on the line 8—8 of Fig. 7;

Fig. 9 is a vertical section illustrating the use of the special form of blocks for constructing air cooled floors for furnaces and the like; 100

Fig. 10 is a top or plan view thereof, partly broken away, showing a horizontal section taken approximately on the line 10—10 of Fig. 9;

5 Fig. 11 is a vertical section similar to Fig. 9, illustrating another form of furnace floor construction, using the special form of blocks in connection with bricks of ordinary shape for the purpose of admitting air into the furnace through the floor, as is sometimes required in connection with oil fired and other furnaces; and

10 Fig. 12 is a top or plan view, partly broken away, showing a horizontal section taken approximately on the line 12—12 of Fig. 11.

15 Referring to the drawings, there are there-
in shown various embodiments of my inven-
tion, but it will, of course, be understood that
modifications may be made therein without
leapting from the spirit of my invention,
and particularly, while typical uses of the
20 special forms of blocks for the purpose of
fabricating walls and floors of furnaces are
shown in the drawings, it will be understood
25 that the invention is not limited to these spe-
cific wall constructions, but that numerous
other arrangements of the special blocks in
various furnace structures will be readily
30 suggested to those skilled in the art, to meet
the requirements which occur in practice.

35 In Figs. 5 and 6 of the drawings, there are
shown in perspective two blocks 18 and 19 of
special form, adapted to be used complemen-
tally to each other in alternate courses of the
furnace lining. Each of these blocks com-
40 prises a main body portion 20, preferably of
a height substantially equal to three bricks
of ordinary shape, and of a width substan-
tially equal to the length of a brick of ordi-
nary shape.

45 The body portion 20 of the block is recessed
as at 21, said recess extending the entire
width of the block. A tongue portion 22 ex-
tends rearwardly from the body portion of
the block, this tongue portion also being pref-
50 erably of the same width as the block, and ex-
tending rearwardly a distance approxima-
tely equal to the width of a brick of ordinary
shape, and being of a thickness equal to that
of a brick of ordinary shape.

55 Vertical passageways extend through the
body portion of the block from the recess 21
to the top or bottom surface, as the case may
be, of the block. In the form of block shown
in Fig. 5, these passageways 23 extend
60 through the central portion of the body of
the block, being preferably circular in shape,
while in the form shown in Fig. 6 the pas-
sageways 24 are semi-circular, so that when
two of the blocks 19 are brought into proper
65 relationship to make all vertical joints stag-
gered in the furnace structure, the circular
port or passageway thereby formed will
70 register with the passageways 23 of the

blocks 18 in the courses above and below the
blocks 19 in a particular course.

The front portions of the blocks are pref-
erably off-set so as to form a projection 25
on one side of each block, and a correspond-
ing recess 26 on the other side thereof. The
70 top and bottom surfaces of the blocks are
also preferably provided with grooves 27, ex-
tending the full width of the block and form-
ing a mortar pocket to effect a better seal be-
75 tween the blocks of successive courses than
would ordinarily be provided by a straight
joint.

In building the furnace wall with blocks
of the form above described, the same are
80 preferably laid up in conjunction with bricks
28 of ordinary shape, as shown in Figs. 1 to
4 of the drawings. The bricks 28, it will of
course be understood, are on the outer face of
85 the wall, and may be of ordinary red brick,
although in some instances, where the temper-
atures are high, it is desirable to use fire
brick.

The blocks 18 and 19 are laid in alternate
courses, and the tongue portions 22 of said
90 blocks extend into the outer portion of the
wall between courses of the bricks 28, said
bricks 28 being turned in certain of the
courses thereof in order to permit said tongue
95 portions 22 of the blocks 18 and 19 to extend
into the portion of the wall formed of the
bricks of ordinary shape, and to be effectively
bonded therewith.

It will, of course, be understood that the
90 bricks 28 of ordinary shape may be laid in
any preferred manner as to their respective
longitudinal arrangement in the wall, and
that where heavier walls are required addi-
tional thickness may be provided by a suit-
able arrangement of said bricks 28.

105 When the wall is laid up as above set forth,
there will be provided horizontal passag-
eways 29, each formed by the juxtaposition of
the horizontal recesses 21 in the blocks 18 and
19, and certain faces of the bricks 28. Like-
110 wise, there will be provided a series of ver-
tical passageways 23 and 24 extending be-
tween the horizontal passageways 29.
Through these passageways cooling air may
115 be circulated by forced or induced draft, in
which manner the lining of the furnace may
be kept at a relatively low temperature and,
as is commonly practiced in connection with
furnaces having air cooled walls, the air cir-
120 culating through these passageways may if
desired be introduced into the furnace, where-
by a supply of preheated air will be avail-
able to aid the combustion therein. The par-
ticular manner of causing the air to be cir-
125 culated through the passageways, and feed-
ing the same to the furnace, forms no part of
the present invention, as the same is well
known and a variety of such arrangements
have been used in practice.

130 A valuable feature of the present invention

resides in the adaptability for easily and conveniently providing baffles in the wall construction, when desired, by the mere insertion of courses of red bricks 30, which may be of ordinary shape, horizontally disposed in certain of the horizontal passageways 29 formed by the recesses 21 (see Figs. 7 and 8).

In Figs. 9 and 10 of the drawings, there is shown a use of the blocks 18 and 19 for the construction of air cooled furnace floors in which the flat faces of both sets of blocks 18 and 19 are disposed downward, and the recessed portions 21 of both sets of blocks are disposed toward the top; and, in the space thus provided, there may be mounted special slabs or tiles 31 which will serve to bridge the space provided by the juxtaposition of the tongue portions 22. When the slabs or tiles 31 are thus placed there will be provided a plurality of horizontally disposed passageways 32 through which cooling air may be circulated.

In Figs. 11 and 12, there is shown another form of floor construction, using the special blocks 18 and 19, but in this instance the flat faces of the blocks 18 and 19 are disposed upward, the tongue portions thereof being supported by two courses of bricks 33 and 34 of ordinary shape, one of said courses preferably being arranged longitudinally and the other transversely thereon. In this manner, there will be formed horizontal passageways 35 between the bricks 33 and 34 and the recesses 21 of the blocks 18 and 19. The horizontal passageways 35 are in communication with the passageways 23 and 24 formed in the blocks 18 and 19, respectively. Any space which may be left, as at 36, between the ends of the tongue portions 22 of adjacent rows 40 of blocks 18 and 19, may be filled in with mortar or cement, as desired.

It will be noted that there is provided a special form of block, particularly adapted for furnace lining, which may be easily and conveniently molded, which when fabricated into a furnace structure will be effectively bonded therein, and which when so fabricated will provide ample passageways for the circulation of cooling air relatively close to the inner surface of the furnace wall, thereby decreasing slagging and erosion, and also decreasing the tendency of the structure to spall when changes in the furnace temperatures take place. It will also be noted that the arrangement is such that baffles may be readily inserted in the wall for the purpose of properly directing the flow of the cooling air through the passageways of the wall, to the end that all portions of the same will be effectively cooled. Furthermore, the special forms of blocks are readily adaptable for floor structures of furnaces, being suitable for the air cooled type of furnace floor as well as for the types of floors wherein it is necessary to admit additional air through said floors.

Having thus described the nature and characteristic features of my invention, what I claim as new and desire to secure by Letters Patent, is:

1. A block for furnace structures having one of its horizontal surfaces disposed substantially in a single plane, the front portion of the block being of a height substantially equal to three ordinary bricks; the intermediate portion of the block being of a height substantially equal to two ordinary bricks, thereby to provide horizontal passageways when the blocks are built in the furnace structure; and the rear portion of the block being of a height substantially equal to an ordinary brick, thereby to provide a bonding tongue; and the block having a passageway extending vertically through the same, thereby to provide communications between the aforesaid horizontal passageways. 70 75 80 85

2. A block for furnace structures having one of its horizontal surfaces disposed substantially in a single plane, the front portion of the block being of a height substantially equal to three ordinary bricks; the intermediate portion of the block being of a height substantially equal to two ordinary bricks, thereby to provide horizontal passageways when the blocks are built in the furnace structure; and the rear portion of the block being of a height substantially equal to an ordinary brick, thereby to provide a bonding tongue; the block having a passageway extending vertically through the same, thereby to provide communications between the aforesaid horizontal passageways; and the front part of the block being offset to provide a projection at one end of the block and a corresponding recess at the other end thereof. 90 95 100

3. A block for furnace structures having one of its horizontal surfaces disposed substantially in a single plane, the front portion of the block being of a height substantially equal to three ordinary bricks; the intermediate portion of the block being of a height substantially equal to two ordinary bricks, thereby to provide horizontal passageways when the blocks are built in the furnace structure; and the rear portion of the block being of a height substantially equal to an ordinary brick, thereby to provide a bonding tongue; the block having a passageway extending vertically through the same, thereby to provide communications between the aforesaid horizontal passageways; and the top and bottom surfaces of the block having a mortar sealing groove extending the full width of the block. 105 110 115 120

4. A block for furnace structures having one of its horizontal surfaces disposed substantially in a single plane, the front portion of the block being of a height substantially equal to three ordinary bricks; the intermediate portion of the block being of a height substantially equal to two ordinary bricks, 125 130

thereby to provide horizontal passageways when the blocks are built in the furnace structure; and the rear portion of the block being of a height substantially equal to an ordinary brick, thereby to provide a bonding tongue; the block having a passageway extending vertically through the same, thereby to provide communications between the aforesaid horizontal passageways; the front part of the block being offset to provide a projection at one end of the block and a corresponding recess at the other end thereof; and the top and bottom surfaces of the block having a mortar sealing groove extending the full width of the block.

In testimony whereof, I have hereunto signed my name.

EDWIN SMILEY.
